UNITED STATES PATENT OFFICE.

JULIUS PEGEL, OF PHILADELPHIA, PENNSYLVANIA, ASSIGNOR TO JOHN BROMLEY & SONS.

DESIGN FOR A RUG.

SPECIFICATION forming part of Design No. 21,022, dated September 1, 1891.

Application filed August 30, 1890. Serial No. 363,559. Term of patent 3½ years.

To all whom it may concern:

Be it known that I, JULIUS PEGEL, a subject of the Emperor of Germany, residing in the city of Philadelphia, State of Pennsylvania, have invented and produced a new and original Design for a Rug, of which the following is a full, clear, and exact description, reference being had to the accompanying drawings, forming a part of this specification.

10 My invention has relation to the surface ornamentation of a rug; and it consists of the design therefor fully illustrated in the accompanying photographic drawing, hereto annexed and made a part of this specification.

15 The distinguishing features of the design are the center-piece marked C C', which is in

the form of an externally-ornamented urn inclosed within an inner border B, and the latter surrounded by an outer border A, consisting of isolated figures on a plain ground. 20

I claim as my invention—

1. The design for a rug, substantially as shown and set forth.
2. The design for the center-piece C C', substantially as shown and described. 25

In testimony whereof I have hereunto affixed my signature this 31st day of July, A. D. 1890.

JULIUS PEGEL.
